UNITED STATES PATENT OFFICE.

JOSEPH HOTCHNER, OF SAN FRANCISCO, CALIFORNIA.

SIGN FRAME.

Application filed March 3, 1919. Serial No. 280,350.

To all whom it may concern:

Be it known that I, JOSEPH HOTCHNER, a citizen of the United States, residing at San Francisco, in the county of San Francisco, State of California, have invented a new and useful Sign Frame, of which the following is a specification in such full and clear terms as will enable those skilled in the art to construct and use the same.

This invention relates to a sign frame and its object is to produce a frame which is capable of holding letters either illuminated or non-illuminated, in a fixed position with respect to the sign in such manner as to make them easily disassembled therefrom as well as readily placed therein.

Another object of the invention is to provide a frame which may be used for either vertical signs or for horizontally extending signs, as may be desired, no holes in the letters being required to secure them in place in the frame.

Other objects of the invention will appear as the description proceeds.

An embodiment of the invention is shown in the accompanying drawings in which the same reference numeral is applied to the same portion throughout, but I am aware that there may be modifications thereof.

In the drawings:

Figure 1 is a front elevation of a horizontally extending sign frame built in accordance with this invention.

Figure 2 is a front elevation of a vertically extending sign frame built in accordance with this invention.

Figure 3 is a front elevation of a letter used in conjunction with the sign frame.

Figure 4 is a transverse sectional view of the sign frame on a slightly enlarged scale, showing the manner of securing letters in place in the sign frame, and

Figure 5 is a view of the interior of the frame for the sign, showing a portion of one of the plates for holding the letters.

The numeral 1 indicates a sign body which has an open frame 2 at the front to receive suitable letters 3. The letters are held in place in the frame 2 by means of plates 4 and 5. The plates are in turn secured in position by means of a series of screws 6 and 7, there being such a number of the screws as is necessary for a given sign.

The letters are shorter in the case of the horizontal sign, and narrower in the case

of the vertical sign than the distance between the centers of the one set of screws and the opposite edge of the opening in the sign frame; so that the letters can be placed in position without taking out the screws and when the letters have been placed in position as indicated in the case of one letter in Figure 2 these screws may be tightened up and will firmly hold the letters in place.

A particular advantage of this construction lies in the fact that with some forms of letters it is not expedient to bore holes in them because of the porcelain covering thereon, and this sign is particularly adapted for that character of work. Whether the construction is used with the vertical sign or with the horizontal sign is a matter dependent only upon the desire of the user.

Having thus described my invention, what I claim as new and desire to secure by Letters Patent of the United States is as follows:

1. A sign comprising a sign body having an opening on one side to receive a series of letters or characters, letter retaining bars extending along two sides of said opening and producing grooves to receive opposite edges of the letters, means for securing one of the bars in place and screws for connecting the other bar in place whereby the letters may be tightened in position in the sign body, the distance between the grooves formed by said bars being sufficient to allow the letters to be inserted in place from the front of the sign and removed therefrom without removing the screws from the securing bar.

2. A sign comprising a sign body having an opening on one side, letter retaining bars extending along two sides of said opening, screws for securing said bars to the sign body, and a series of letters held in place by said bars, said letters being of a dimension at right angles to the securing bars less than the distance from the screws in one of said bars to the opposite side of the opening in the sign body whereby the letters may be inserted in place, from the front and removed from the sign body without removing the screws from said securing bars.

In testimony whereof I have hereunto set my hand this 20th day of February A. D. 1919.

JOSEPH HOTCHNER.
